(57) **CLAIM**

The ornamental design for an icon for a portion of a display screen, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of an icon for a portion of a display screen showing our new design.

The broken line showing of the display screen is for illustrative purposes only and forms no part of the claimed design.
